UNITED STATES PATENT OFFICE.

HENRY M. SHEER, OF QUINCY, ILLINOIS.

HEATING SYSTEM FOR BROODERS, INCUBATORS, AND THE LIKE.

Application filed March 25, 1921. Serial No. 455,476.

To all whom it may concern:

Be it known that I, HENRY M. SHEER, residing at Quincy, in the county of Adams and State of Illinois, a citizen of the United States, have invented certain new and useful Improvements in Heating Systems for Brooders, Incubators, and the like, of which the following is a specification.

This invention relates to heating systems for brooders, incubators, and the like, and one object is to provide, in combination with a visible manually-operated oil-feed, a means to facilitate the initial starting of the burner by which, after the predetermined depth of the oil in the burner for starting is effected and the burner lighted, the operator is assured of nothing greater than the predetermined feed of oil to the burner.

Another object of the invention is to provide an overflow means, by which the burner proper is prevented from overflowing, causing a mess under the canopy or around the incubator in case the flame should accidentally go out.

25 In the accompanying drawings:—

Fig. 1 is a perspective view of my complete device;

Fig. 2 is an enlarged detail view of the overflow arrangement.

30 The numeral 1 indicates a burner, connected to which is an oil-font 2 supported by a base 3, by means of a vertical feed-pipe 4. Leading from the base is a horizontally-arranged feed-pipe 5, the major portion of which is arranged horizontally and in close proximity to the floor, allowing free movement of the chicks beneath the canopy when used in connection with that type of brooder. Said pipe 5 is supported near its outer end 40 by a bracket 6, which, together with the base 3, provides a suitable support for the heating system. The outer end of the feed-pipe 5 is preferably bent upwardly, and then horizontally as at 5' just prior to entering the burner, acting as a support for the burner. The oil-font 2 is preferably provided with suitable brackets 7, which are adapted to receive an oil reservoir 8, which, in this instance, is made of glass, provided 45 with stopper controlling mechanism 9 adapted to be actuated after the glass reservoir is inverted and its open end placed within the oil font 2. A bracket 10 is adapted to directly support the oil font, said bracket 50 having formed in its outer end a visible oil chamber 11.

Mounted upon the bracket 10 directly above the visible oil feed is a casting 12, having arranged horizontally therein a spring actuated needle valve 13. The casting 12 60 is provided with an upwardly and horizontally projecting arm 14 at the top, and this carries a minimum and maximum adjusting screw, 15 and 16, respectively, they being located at a point where they are easily 65 accessible and easy to manipulate. At its lower end, and beneath the valve 13, the casting has a pair of lugs 14.

The valve-controlling lever 18 is fulcrumed between these lugs 14 on the pin 19, the arm 70 of this lever above the fulcrum, extending in the path of, and in close proximity to, the protruding end of the needle-valve 13, and its extreme upper end in the space between the inner end of the minimum and 75 maximum adjusting screws 15 and 16, by which its adjustment is regulated. An auxiliary lever 20 is also fulcrumed on the pin 19 alongside the controlling lever 18, and its upper end also extends into the path of 80 the protruding end of the needle-valve 13. Thus auxiliary lever 20 has a flange 21 at one edge, which overlaps the outer edge of the lever 18, so that when lever 18 is swung in one direction, the auxiliary lever 20 moves 85 with it, whereas the latter is free to swing independently of the lever 18 in one direction, as is also lever 18 independent of lever 17 in one direction. An auxiliary adjusting screw 21 screws into the threaded eye 22 of 90 the lower end of the auxiliary lever 20. By means of the auxiliary lever, the needle-valve can be opened or closed without deranging or changing in the least the position of the minimum or maximum adjusting- 95 screws 15 and 16 at the top of the valve. Without this auxiliary adjustment 21, it is necessary to use the maximum adjusting screw to close the needle-valve 13 and shut off the oil. Of course, this also makes it 100 necessary to change the position of the minimum adjusting screw 15.

Arranged adjacent the burner is a thermostatic regulator 23, which is adjustably supported upon the feed-pipe bracket 6. The 105 adjusting-lever 24 of the thermostat and the actuating lever 18 of the oil font are connected together by connecting-rod 25; this construction effecting an accurate control of the valve 13, according to the variations of 110 the temperature, causing the thermostat 23 to either contract or expand and transmit a

relative movement to the spring-valve 18.

As is apparent, the visible oil feed enables the operator to determine both the minimum and maximum flow of oil, counting the number of drops of oil passing through the visible oil-chamber, and it is not necessary for the operator to wait for the flames to fully respond to prevent a possible overflow of the burner in case the flame 10 should be extinguished, or that there were too great a flow of oil for the burner to properly consume, for I connect to the vertical feed-pipe 4 an overflow valve 26, which, as shown in Fig. 1, is at such an elevation 15 along the feed-pipe 4 as to be in horizontal alignment with the outer horizontal portion 5' of the horizontal feed-pipe 5. Arranged directly beneath this valve is a suitable receptacle 27 removably secured to the 20 base 3 on the vertical feed-pipe 4, which is adapted to receive the overflow from the valve 26, thereby preventing any oil spilling over at the burner.

The operator in starting up the heater 25 will level it so that when the oil ceases to run out of the overflow valve 26, it will show a predetermined depth in the bottom of the oil groove in the burner 1. After securing this level, the operator will close the 30 overflow valve 26, priming the burner 27 with gasoline, lighting it, and waiting a few seconds for the flame to get started. Then he will turn on the oil in the visible oil feed so it will give the burner the proper number 35 of drops for the size flame desired.

The overflow valve 26 is then opened, and the operator can immediately go away, and the burner takes care of itself, the overflow taking care of any possible excess flow 40 above a certain predetermined level, and also taking care of the natural flow should the flame for any reason be accidentally extinguished.

It will thus be seen that I have provided 45 an overflow or regulating means of simple character, which, in combination with the manually-actuated valve-mechanism and visible feed produce an apparatus which is practically automatic, doing away with 50 practically all personal attention on the part of the operator, after the burner is initially started.

I claim:

1. A heater comprising a burner adapted 55 to burn a liquid fuel, a reservoir for the liquid, automatically controlled means inter-

posed between the reservoir and the burner for regulating the fuel supply to the burner, and an overflow interposed between the reservoir and the burner and arranged in 60 horizontal alignment with the oil groove of the burner adapted to regulate the height of the oil in the burner.

2. A heater comprising a burner adapted to burn a liquid fuel, a reservoir arranged 65 above the burner and a feed-pipe connected between said burner and reservoir, the portion thereof adjacent the reservoir arranged vertically, oil-controlling means arranged adjacent the reservoir, and an over- 70 flow means arranged in the vertical portion of the feed-pipe in horizontal alignment with the oil level in the oil groove of the burner.

3. A portable heating system comprising 75 a base, a container arranged above said base, a burner, a feed-pipe arranged between said container and burner, portions thereof adjacent the container arranged vertically, oil- 80 control means arranged adjacent the container, and an overflow valve arranged in the vertical portion of the feed-pipe adjacent the container in horizontal alignment with the oil level in the oil groove of the burner.

4. The combination of an oil container, a base, a burner, feed-pipes arranged between said base, container and burner, the pipe extending between the base and burner arranged in close proximity to the floor, oil 90 controlling means interposed between the container and burner, an overflow valve arranged in the feed-pipe extending between the container and burner arranged in horizontal alignment with the oil groove of the 95 burner.

5. A heater comprising a burner adapted to burn a liquid fuel, a reservoir arranged above the burner, a feed-pipe connected between said burner and reservoir, a portion 100 thereof adjacent the reservoir arranged vertically, oil controlling means arranged adjacent the reservoir, a sight-feed interposed between the reservoir and burner, and an overflow means arranged in the vertical portion of the feed-pipe below the sight-feed 105 and in horizontal alignment with the oil level in the oil groove of the burner.

In testimony whereof I hereunto affix my signature.

HENRY M. SHEER.
